KNITTING MACHINE

Arnold Verbeek, Wustenbrand, Germany, assignor to Kalio, Inc., New York, N. Y., a corporation of New York

Application November 28, 1936, Serial No. 113,163
In Germany December 6, 1935

9 Claims. (Cl. 66—110)

The present invention relates to improvements in knitting machines, and more particularly to a novel and improved braking device for controlling the operation of the sinkers of a flat knitting machine having a series of needles movable as a unit, and independently movable yarn measuring sinkers.

It is the usual practice in machines of this general description, to provide spring members preferably cam controlled which operate to engage the sinker jacks and maintain the sinkers in their fully advanced yarn sinking position to insure a uniform kinking of the feeding yarn. In the usual flat full-fashioned knitting machines, these springs are supported on a jack spring bar, and are arranged for engagement with the sinker jacks to maintain the jacks and sinkers controlled thereby in their fully advanced position during the subsequent advance of the dividers. It has been found, however, that under certain operating conditions as, for example, when loops of different lengths are being knitted in the same course, that the increased yarn tension on the shorter loops tends to cause the jack springs to be forced out of their supporting position, so that an uneven formation of the loops in the finished fabric results.

It is a principal object of the present invention to provide a sinker braking device which may be applied to secure a substantially uniform frictional braking action against movement of the sinkers from their fully advanced yarn sinking position, and thereby to insure a more uniform and efficient operation of the machine for the production of even appearing fabric.

With this and other objects in view as may hereinafter appear, a principal feature of the invention consists in the provision of a braking device which is arranged to engage against and force laterally the unsupported portion of the sinkers extending across a cut-away portion of their grooves in the sinker head, and thereby to secure a frictional braking action against movement of the sinkers in their grooves which is automatically regulated for each individual sinker by the resistance of the sinker element to the bending action referred to.

The several features of the invention consist also in the devices, combinations and arrangement of parts hereinafter described and claimed, which together with the advantages to be obtained thereby will be readily understood by one skilled in the art from the following description taken in connection with the accompanying drawing which discloses the application of the present

invention to a flat knitting machine, only so much of the machine being shown as is believed necessary to illustrate the connection of the invention therewith.

Fig. 1 is a fragmentary view in front elevation showing the right hand end of the sinker head, the brake slide, and means for controlling the same;

Fig. 2 is a cross sectional view of the sinker head illustrating the alternating jack sinkers and dividers and the usual catch bar for controlling the operation of the dividers;

Fig. 3 is a plan view of the sinker head with the top portion removed showing the brake slide in inoperative position;

Fig. 4 is a view similar to Fig. 3, but with the brake slide moved to the left into braking position; and

Fig. 5 is a somewhat diagrammatic plan view showing the sinkers and dividers in their fully advanced positions in sinking a course of loops during the knitting of the high heels.

The invention is herein disclosed as embodied in a flat full-fashioned knitting machine of ordinary description having the usual spring beard needles 25 indicated in Fig. 4, movable as a unit with relation to a fixed press edge 12, independently movable yarn measuring sinkers 14 alternating with dividers 16, and a sinker head comprising the sinker bed 18 grooved to receive the alternating sinkers and dividers and a cover 20 similarly grooved for guiding the sinkers and dividers. The sinker head is supported at intervals throughout its length on supporting frames such as that indicated at 22 in Figs. 1 and 2 forming 30 part of the fixed structure of the machine. The sinker bed 18 is constructed in the usual manner with a cut-away portion 24, and the cover 20 is similarly provided with a cut-away portion 26 so that the sinkers and dividers are unsupported 35 by their grooves over a considerable portion of their length within the sinker head. The sinkers are successively advanced to sink yarn by means of the usual sinker jacks 28 and slur cock 30. The machine is also provided with a catch bar 32 40 which operates in the usual manner to advance the dividers 16 to re-measure the sunk yarn against the shanks of all the needles, and thereafter to retract both sinkers and dividers preparatory for the knitting of another course. 45

In the preferred form of the invention herein disclosed, a braking device for maintaining the jack sinkers in their fully advanced position is provided, which comprises a brake slide 34 supported in a guideway 36 in the sinker head 18 55

and extending throughout the length of the same. The slide 34 is provided with upwardly extending lugs 38 grooved to receive the jack sinkers 14 which are freely slideable therein. Relatively 5 wide spaces 39 (see Fig. 1) are provided between these lugs, so that ample room is provided for the movement of the dividers 16 which are unaffected by the lengthwise movement of the slide 34 to brake the movement of the sinkers as here- 10 inafter set forth. As best shown in Fig. 2 of the drawing, the slotted lugs 38 are located on the slide 34 to extend upwardly into approximately the central part of the cut-away portion 24, so that they operate against substantially the 15 middle of the unsupported portions of the sinkers in the sinker head 18.

The operation of the braking slide 34 is conveniently controlled in timed relation to the operation of the machine by the mechanism shown 20 in Fig. 1, which comprises a cam lever 40 supported on a fixed pivot 42, and arranged at its upper end to engage against the right hand end of the slide 34. A cam roll 44 mounted on the lever engages against a cam 46 supported on a 25 shaft 48 which may be driven through any convenient connections in synchronism with the usual main cam shaft of the machine. A tension spring 50 connected at one end to the lever 40 and at its other end to a point on the machine 30 frame, acts to maintain the lever 40 and roll 44 in operative engagement with the cam 46.

The operation of applicant's sinker braking device is as follows: At that point in the knitting cycle at which the slur-cock 30 has completed 35 its movement to advance the sinkers successively to yarn kinking position, the roller 44 rides onto a low portion of its cam, so that the lever 40 is permitted to swing under the influence of its spring 50 to move the brake slide 34 to the left 40 as shown in Fig. 5, causing the slotted members 38 to engage against the sides of and bend the unsupported portions of the sinkers laterally (see Fig. 4), thus providing a frictional resistance to any backward movement of the sinkers as the 45 dividers 16 are simultaneously advanced by the action of the catch bar 32 to re-kink the yarn against the shanks of all the needles. It will readily be seen that an extremely even braking action is applied against the sinkers which is 50 automatically determined for each individual sinker by the stiffness of the sinker element and by the amount of bend produced by the movement of the slide 34. With the construction shown, the advance of the dividers 16 is in no way impeded or interfered with due to the existence of the relatively wide spaces 39 through which the dividers pass between the sinker braking lugs 38. After the catch bar 32 has been brought to 55 its extreme forward position, re-kinking the yarn firmly against all of the needle shanks, and is then dropped into engagement with the butts of the sinkers 14, the brake slide 34 is again moved to the right to its initial position as shown in Fig. 3, as the roll 44 again rides onto the high portion of its cam 46. The movement of the slide 34 to the right to its inoperative position is assured by the spring quality of the sinkers 14 which immediately tend to straighten out, carrying the slide 34 to the right when released by the 60 return of the lever 40 to its inoperative position shown in Fig. 1.

With this construction and arrangement of the braking mechanism, it will readily be seen that the sinkers are permitted to move freely in their 65 slots during the operation of the slur-cock cam,

and again as they are withdrawn by the retracting movement of the catch bar 32. The construction illustrated has the very considerable advantage that the chance of faulty operation of the mechanism for maintaining the sinkers in their advanced yarn sinking position due to wear on the parts, is substantially eliminated, since any such wear as may take place is automatically taken up by the spring quality of the sinker elements. The braking mechanism above described is also 10 of advantage in that the braking action is applied thereto only at the time when the sinkers are to be maintained in fully advanced position, and permits of the free movement of the sinkers to and from yarn sinking position under the influence respectively of the slur-cock 30 and catch bar 32. A further advantage of the present construction consists in the fact that the braking action against the sinkers is continuously and evenly applied, thus eliminating or reducing to a 20 minimum the possibility of faulty operation of the sinkers which might otherwise result from failure of the braking device to hold the sinkers in their extreme forward position. An example of this condition is illustrated in Fig. 5, which 25 illustrates the kinking of a course of loops during the knitting of the high heels, in which relatively long loops are formed on the high heel sections, and relatively small loops are being knitted on the intermediate portion of the needles, so 30 that the intermediate needles are forced forwardly a relatively greater extent by the advance of the dividers to re-kink the yarn, thus causing a considerably greater strain to be thrown onto the sinkers cooperating with this group of needles. 35 The additional strain against the sinkers kinking small loops may with known mechanisms force the sinker elements rearwardly a slight amount. With applicant's device, such movement, however, is prevented by the continued 40 braking action against the sinkers, which serves to prevent any irregularity in the lengths of the finished loops.

While the invention is herein disclosed as applied to a fine gauge machine to maintain the 45 sinkers in their forward position only during the advance of the alternating dividers, it will be understood that the present invention in its broader aspects may be equally well applied to a machine of this general description in which 50 dividers are not employed, and further that variations may be made in the construction and timing of the braking mechanism to cause a frictional braking action to be applied against the sinkers at a relatively earlier point in the operating cycle as the sinkers are advanced by the 55 operation of the usual slur-cock to kink the feeding yarn.

The invention having been described, what is 60 claimed is:

1. In a knitting machine having needles movable as a unit and yarn measuring sinkers, the combination of a sinker bed in which the sinkers are slidably supported, means for successively advancing the sinkers to sink yarn against the needle shanks, braking means arranged for engagement with the sinkers to arrest the sliding movement of the sinkers, and means for actuating said braking means during each knitting cycle to permit a free advancing movement of the sinkers, and thereafter to produce a frictional resistance against movement of the sinkers. 65

2. In a knitting machine having needles movable as a unit, independently movable yarn meas- 70

uring sinkers and dividers, the combination of a 5
sinker bed in which the sinkers and dividers are
slidably supported, means for successively ad-
vancing the sinkers to sink yarn against the
needle shanks, braking means arranged for fric-
tional engagement with the sinkers only to ar-
rest sliding movement of the sinkers, and means
for actuating said braking means during each
10 knitting cycle to permit a free advancing move-
ment of the sinkers, and thereafter to produce
a frictional resistance against movement of the
sinkers.

3. In a knitting machine having needles move-
able as a unit, independently movable yarn meas-
uring sinkers and dividers, the combination of
15 a sinker bed in which said sinkers and dividers
are slidably supported, means for successively
advancing the sinkers to sink yarn against the
needles, a catch bar operable to advance the di-
viders and thereafter to retract the sinkers and
20 dividers, sinker braking means for frictionally
resisting the sliding movement of the sinkers,
and means for actuating said braking means to
relieve said frictional resistance during the ad-
vancing movement of the sinkers and to main-
25 tain a substantial braking action against back-
ward movement of the sinkers during the ad-
vance of the dividers.

4. In a knitting machine having a series of
30 needles movable as a unit, successively operable
yarn measuring sinkers and dividers, a sinker
bed in which said sinkers and dividers are slid-
ably supported, a sinker braking device compris-
ing a member arranged for movement length-
35 wise of the needle series to frictionally engage
each of said sinkers, and cam means for con-
trolling the operation of said braking member
to relieve said frictional engagement during the
yarn measuring operation of said sinkers, and
40 thereafter to frictionally engage the sinkers.

5. In a knitting machine having a series of
needles movable as a unit and yarn measuring
sinkers, the combination of a sinker bed having
45 formed therein grooves to receive the sinkers
and a portion thereof cut away leaving an inter-
mediate portion of the said sinkers unsupported
by said grooves, and a sinker braking device com-
prising a slide supported for movement length-
wise of the needle series and having members
50 arranged for frictional engagement against the
side of each of said sinkers passing across said
cutaway portion, and means for moving the slide
and said members supported thereon to bend
laterally the unsupported portion of each of said
55 sinkers.

6. In a knitting machine having a series of
needles movable as a unit and yarn measuring
sinkers, the combination of a sinker bed having
formed therein grooves to receive the sink-

ers, and a portion thereof cut away leaving an
intermediate portion of the said sinkers unsup-
ported by said grooves, a sinker braking device
comprising a slide supported for movement
lengthwise of the needle series and having means
arranged for frictional engagement against the
side of each of said sinkers passing across said
cut-away portion, means for moving the slide and
said members supported thereon to bend
laterally the unsupported portion of each of said
10 sinkers, and cam means for controlling the op-
eration of said means for moving the slide to
bend the sinkers and thereby to impart a brak-
ing action against a rearward movement of the
sinkers from yarn sinking position. 15

7. In a knitting machine having a series of
needles movable as a unit, independently move-
able yarn measuring sinkers and dividers, the
combination of a sinker bed grooved to receive
the sinkers and dividers and having a cut-away 20
portion extending along its length to leave an
intermediate portion of said sinkers unsupport-
ed by the grooves, means for advancing the sink-
ers to sink yarn against the needles, a catch bar
for advancing the dividers and thereafter for re-
tracting the sinkers and dividers, and a sinker
25 braking device comprising a slide movable length-
wise of the sinker bed and having members ar-
ranged for frictional engagement against the
side of each of said sinkers passing across said
30 cut-away portion of the bed, and means for mov-
ing the slide to bend said unsupported portion
of each of said sinkers during the advance of
the dividers.

8. In a knitting machine having a series of
needles movable as a unit, independently move-
able yarn measuring sinkers and dividers, the
combination of a sinker bed grooved to receive
the sinkers and having a cut-away portion leaving
40 an intermediate portion of each of said sinkers
unsupported by its groove, a slide supported
in said cut-away portion for movement length-
wise of the sinker bed and having formed there-
in relatively narrow grooves to receive the sink-
45 ers and relatively wide grooves to receive the
dividers, and means for moving said slide to fric-
tionally engage and to bend the sinkers only
against the sides of their grooves.

9. In a knitting machine having a series of
needles movable as a unit and independently
moveable yarn measuring sinkers, the combination
of a sinker bed grooved to receive the sinkers
50 and having a cut-away portion leaving an in-
termediate portion of each of said sinkers un-
supported by its groove, and means for bending
the unsupported portions of the sinkers to fric-
tion the sinkers against movement in their
55 grooves.
